UNITED STATES PATENT OFFICE

2,430,036

TEAR-STRIP TYPE CONTAINER AND
RECLOSURE THEREFOR

Ivan D. Thornburgh, Leonia, and Frank W. Goodrich, Newark, N. J., assignors to American Can Company, New York, N. Y., a corporation of New Jersey

Application December 11, 1944, Serial No. 567,660

1 Claim. (Cl. 220—54)

1

The present invention relates to a metal air-tight tearing strip container or can having an interior collar arranged inside of the tearing strip and has particular reference to a container of this type which can be reclosed with an air-tight seal after the container is opened by removal of the tearing strip and in reclosing position will be securely locked by engagement of the cover with the collar.

The usual hermetically sealed container when once opened by removal of the tearing strip can only be re-covered as contradistinguished from resealed by the detached can cover. It is true that when the can is opened air comes into contact with the product and this air is present and ordinarily cannot be removed. For many products the circulation of air in the open container is not objectionable especially when the remaining product is quickly consumed.

Some products, such for example as coffee, dried milk and other powdered dairy products, will keep much better if additional air is prevented from circulating into and through that portion of the product which has not been removed and which remains in the open can. In other words an air-tight reclosure for cans of this general type is desirable and the present invention contemplates an improved can construction of an interior collar can which is so designed as to insure a simple and efficient air-tight reclosure without impairing in any way the efficiency of an easily opened hermetically sealed can.

An object of the present invention is the provision of an improved construction for a tearing strip container having an interior collar wherein, in addition to the usual air-tight sealing of the can when it is initially closed on its contained product, there is also provided an air-tight reclosure.

Another object of the invention is the provision of a tearing strip container having an interior collar which is so formed as to adapt that part of the can for air-tight resealing by the reclosure cover which has been removed in opening the can.

Yet another object is the provision of an easily opened tearing strip collar container wherein the cover has double gasket lined regions, the reclosure cover being formed in such a manner as to provide locking engagement with the collar of the opened can as in a bayonet joint, thereby insuring an air-tight sealing reclosure which in no way impairs the initial opening and subsequent reopenings of the can.

Numerous other objects and advantages of the

2

invention will be apparent as it is better understood from the following description, which, taken in connection with the accompanying drawings, discloses a preferred embodiment thereof.

5 Referring to the drawings:

Figure 1 is a perspective view of a tearing strip container embodying the present invention;

Fig. 2 is partly a sectional view and partly an 10 elevation drawn to an enlarged scale with parts broken away the position of the section being taken substantially along the lines 2—2 in Fig. 1;

Fig. 3 is a view similar to the sectional view of Fig. 2 but taken in a different position radially 15 of the can;

Fig. 4 is a sectional view similar to Fig. 3 illustrating the position of parts after the container has been opened and reclosed; and

Fig. 5 is a plan sectional view of the container 20 taken substantially along line 5—5 in Fig. 4, but drawn to a smaller scale.

The present invention may be applied to a container having a body 11 and end closures 12 secured to the body in double seams 13. The 25 novelty of the container illustrating the present invention is associated with its upper or top end while the usual conventional bottom end may be used.

30 Adjacent the top and just below the upper end seam 13 the body wall 11 is scored with a pair of parallel score lines preferably cut on the inside surface of the container body wall. These include a lower score line 15 and an upper score line 16 setting off a tearing strip 17. At 35 the side seam of the container the tearing strip terminates in an extended tongue 18 which provides for engagement of the usual opening key.

The body wall above the score line 16 merges into the top double seam and a sealing gasket 40 19 located in the usual sealing gasket channel is interposed between the body and cover parts in the conventional double seam. This portion of the body wall which is detached from the rest 45 of the body wall 11 by removal of the tearing strip and which remains with the top end 12 is designated by numeral 20.

A collar 21 is located in the can body 11 and in the upper part of the body. To properly locate the collar, both collar and body walls are beaded together, there being an outwardly bowed collar bead 22 seated within a corresponding body bead 23. An air-tight joint is formed between the collar and the body wall and this may take the form 50 of a soldered joint 24 which extends all of the

way around the collar at or adjacent its lower edge.

The collar 21 above the bead 22 extends in close engagement with the body wall to a position just above the upper score line 16. The collar wall then bends inwardly at a rounded annular corner 25 to merge into a conical wall 26 which extends upwardly and inwardly at about 45° from the horizontal. The upper portion of the conical wall terminates in an inwardly curled edge or friction seat 27, this curl being open and slightly resilient and providing a smooth mouth for the container when open.

The top end 12 when in seamed position extends downwardly inside the body wall section 20 and inside of the top double seam 13 to a depth just below the double seam. This is the usual chuck countersink for the can cover. This countersunk wall merges into a rounded corner 31 which forms a connection for an integral inverted conical wall 32. At the top, the conical wall bends over in the form of an annular arched section 33 which extends down into a vertical friction wall 34. At the bottom the friction wall 34 merges into a rounded corner 35 which directly connects with an upwardly and inwardly extending conical wall 36 which is substantially parallel to but is inside of the conical wall 32. Wall 36 merges by way of a rounded corner 37 into a flat central panel 38.

The annular arched section 33 which joins the inverted conical wall 32 with the friction wall 34 provides an inwardly spaced reclosure gasket channel for a sealing gasket 39. It will be apparent that the gasket 19 of the double seam 13 and the gasket 39 of the spaced reclosure gasket channel constitute dual gasket sealing regions for the can cover.

When the cover 12 is first seamed onto the body 11, the vertical friction wall 34 of the cover frictionally engages with the collar, as shown in Figs. 2 and 3. More specifically the rounded corner 35 of the cover engages in the friction seat curl 27 of the collar. In this position, the sealing gasket 39 is spaced above and in vertical alignment with the friction seat curl 27. This frictional engagement of the parts 27, 35 is not an air-tight connection but is sufficient usually to keep the container contents within the collar.

When the tearing strip 17 is removed and the container is opened, the cover is detached from the container merely by lifting it from its seated position. When the cover is again applied to the opened container for resealing of the container, it is again brought into position so that the friction wall of the cover engages inside of the collar. From this position, the cover is pressed down into the container so that the vertical wall 34 of the cover slides along the inside of the friction seat curl 27 of the collar. In its fully reclosed position, the can parts are as shown in Fig. 4, the collar curl 27 then being embedded in the sealing gasket 39 of the cover.

Provision is made for positively locking the removed cover onto the can in its reclosing and resealing position. For this purpose the body wall portion 20, which it will be recalled was above the upper score line 16, is formed so that it may be locked with the collar. A plurality of inwardly projecting protuberances or buttons 42 are equally spaced in the wall 20. Three such protuberances are illustrated in Fig. 5.

The outer wall of the collar 21 just below the corner 25 is formed with a plurality of bayonet slots 43, there being a corresponding slot for each

protuberance 42. Each bayonet slot is composed of a vertical groove 44 which extends down from the corner 25 of the collar and merges into an angular transversely extending groove 45. At the time the can cover is seamed on to the can body the protuberances 42 in the body wall are disposed above the collar corner 25 and therefore it is not necessary that the cover be oriented in any particular relation to the can body.

10 After removal of the tearing strip and opening of the can and when the cover is to be applied in a reclosing position it is necessary first to position the cover relative to the open container, so that each protuberance 42 aligns with the corresponding groove section 44 of the bayonet joint 43. From such an aligned position the cover can be pressed down to bring each protuberance into the open end of the associated transverse groove 45.

15 When this lowered position is reached, it is merely necessary to give the cover a slight rotation to move the protuberance 42 along the transverse groove sections 45 and in so doing the angular ceiling edge of each transverse groove 25 acting on its protuberance causes a positive locking of the cover into its reclosure position. It is during this partial rotation of the cover relative to the container that the gasket 39 is pressed down against the open resilient yielding curl 27 30 of the collar 21 so that this curl is embedded in the gasket. This provides an air-tight or hermetic reclosure for the opened container.

Such a can may be reopened and reclosed a number of times, it being necessary in removing the reclosure cover merely to give the cover a slight rotation in an opposite direction so that the protuberances 42 ride up on the lower incline of the groove sections 45 into alignment with the corresponding vertical groove sections 44. 40 In this position, the cover may be lifted from the container.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

In an air-tight sheet metal container capable of air-tight reclosure, a container body having score lines defining a removable tearing strip for opening the container, a collar located inside of said body and hermetically secured thereto, said collar being disposed opposite to and inside of said tearing strip and inclined inwardly and upwardly and terminating in a friction seat adjacent the top of the incline, a container cover secured to said body and extending inwardly and upwardly parallel with and spaced above said inclined collar and curved inwardly to form an inner reclosure gasket channel and thence extending downwardly to form a friction wall fitting within said friction seat of the collar in an initial position and after the container has been opened fitting in another reclosure position with the inclined walls of said cover and collar in closely adjacent position, said cover having an outer primary sealing gasket channel, separate sealing gaskets in said inner and outer cover channels for hermetically sealing the cover on the container body by the primary sealing gasket 65 only when the cover is in its initial position and

for hermetically sealing the opened container by said reclosure gasket engaged between said collar and the cover in its reclosure position after the tearing strip has been removed.
